US00D997928S

(12) **United States Design Patent** (10) **Patent No.:** **US D997,928 S**
Hyun et al. (45) **Date of Patent:** **** Sep. 5, 2023**

(54) **STAND FOR ELECTRONIC DEVICE**

(71) Applicant: **SPIGEN KOREA CO., LTD.**, Seoul (KR)

(72) Inventors: **Chang Hoon Hyun**, Seoul (KR); **Jae Hong Cho**, Seoul (KR)

(73) Assignee: **SPIGEN KOREA CO., LTD.**, Seoul (KR)

(**) Term: **15 Years**

(21) Appl. No.: **29/652,944**

(22) Filed: **Jan. 15, 2021**

(51) **LOC (14) Cl.** **14-03**

(52) **U.S. Cl.**

USPC **D14/252**; D14/224

CLAIM

The ornamental design for a stand for electronic device, as shown and described.

DESCRIPTION

FIG. 1 is a front perspective view of a stand for electronic device showing our new design;
FIG. 2 is a rear perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof; and,
FIG. 8 is a bottom plan view thereof.

1 Claim, 8 Drawing Sheets
